UNITED STATES PATENT OFFICE

GUY ETHAN ALLING, OF ATHOL, MASSACHUSETTS, ASSIGNOR TO ATHOL MANUFACTURING COMPANY, OF ATHOL, MASSACHUSETTS, A CORPORATION OF MASSACHUSETTS

DESIGN FOR ARTIFICIAL LEATHER OR LIKE COATED FABRIC

Application filed April 2, 1930. Serial No. 35,109. Term of patent 3½ years.

To all whom it may concern:

Be it known that I, GUY ETHAN ALLING, a citizen of the United States, residing at Athol, in the county of Worcester and Commonwealth of Massachusetts, have invented a new, original, and ornamental Design for Artificial Leather or like Coated Fabric, of which the following is a specification, reference being had to the accompanying drawing, forming part thereof, in which the figure is a plan view of a piece of artificial leather embodying my new design, a unit of which is contained between the intersecting points of the dot and dash lines, and such unit is repeated in the relation shown.

I claim:

The ornamental design for artificial leather or like coated fabric, as shown and described.

Dated this 28th day of March, 1929.

GUY ETHAN ALLING.
